UNITED STATES PATENT OFFICE.

OSCAR A. ALBRECHT, OF GRAND RAPIDS, MICHIGAN, ASSIGNOR TO O. A. ALBRECHT COMPANY, OF OMAHA, NEBRASKA, A CORPORATION OF NEBRASKA.

FRICITION-GEARING.

1,277,167.

Specification of Letters Patent. Patented Aug. 27, 1918.

Application filed September 25, 1916. Serial No. 121,960.

To all whom it may concern:

Be it known that I, OSCAR A. ALBRECHT, a citizen of the United States, residing at Grand Rapids, county of Kent, and State 5 of Michigan, have invented certain new and useful Improvements in Friction-Gearing, of which the following is a specification.

This invention relates to friction gearing.

The mesh of the braid formed by a braid- 10 ing machine depends wholly upon the speed at which the woven braid is picked up or delivered from the machine.

The present invention has for its object 15 the provision of means controlling the speed of the pick-up or delivery mechanism of a braiding machine adapted to cause the formation of a braid having alternate closely and loosely woven sections.

My invention contemplates the provision 20 of an automatic speed-changing mechanism, coöperating with the drive shaft and the pick-up or delivery rolls of a braiding machine whereby the latter are alternately driven relatively fast and relatively slow 25 and hence alternately pull the braid fast and slow to effect the result heretofore set forth.

The invention is not restricted to use 30 with any particular braiding machine and it may be applied to the pick-up or delivery rolls of the machine set forth in my Patent No. 1,073,558, dated September 16, 1913, or to any other braiding machine.

When a braiding machine is provided 35 with my improvements it is adapted to form a braid such as set forth and claimed in my application for braided lacing cords executed September 8, 1916.

One embodiment the invention may assume is set forth hereinafter and shown in 40 the accompanying perspective drawing.

On the take-off drive shaft A operated from the braiding machine is a cone pulley B and alongside is an auxiliary or counter-shaft C carrying cone pulley D. The 45 pulley D and shaft C are driven from shaft A and pulley B by a friction ring E, preferably of leather.

Worm gears F, G on shaft C and roll- 50 driving shaft H constitute means for transmitting the drive to the usual intergeared pick-up or delivery rolls I, I', I² mounted in standards J, J' of the braiding machine.

A standard J² which has a bearing for shaft H, also supports a revoluble shaft L. Change speed gears K, K' connect shafts 55 H, L.

M is a peripheral cam wheel fixed on shaft L and having a cam groove M' composed of alternate "dwell," with connecting inclines.

A bell-crank-lever N, pivoted to standard J² at Y, has the end N' of one of its arms entering cam groove M' and its other arm provided with a loop N² loosely interlinked with the ring E.

The gears K, K' being removable, any desired change gears, representing any gear ratio, may be employed as it will be understood that the ratio of these gears determines the lengths of braid woven between 70 changes from closely to loosely woven structure.

The pick-up or delivery rolls I, I', I² are driven alternately fast and slow, relatively speaking, due to the shifting of the friction 75 ring E by the action of cam groove M' on bell-crank-lever N and consequently the rolls I, I', I² pick up or deliver the braid either relatively fast or slow and, as previously set forth, alternate lengths are 80 woven closely and loosely.

As the invention is susceptible of modification without changing the essential principle thereof, I do not limit myself to the precise embodiment herein set forth.

Having thus described my invention, what I claim as new and desire to secure by Letters Patent, is:

1. An automatic selective-change-speed drive for the delivery rolls of a braiding machine comprising a roll-driving shaft, a cam shaft, a cam on said shaft, intermeshing removable change-speed-gears on the roll-driving shaft and cam shaft which permit selective changing of the gear-ratio by the substitution of other change-speed gears therefor, variable speed driving means operatively connected to the roll-driving shaft, and a speed controller therefor operated by the cam.

2. An automatic selective-change-speed drive for the delivery rolls of a braiding machine comprising a roll-driving shaft, a cam shaft, a cam on said shaft, intermesh-

ing removable change-speed gears on the roll-driving shaft and cam shaft which permit selective changing of the gear-ratio by the substitution of other change-speed gears therefor, a drive shaft, a counter-shaft, gearing connecting the counter-shaft to the roll-driving shaft, cone pulleys carried by the drive shaft and counter-shaft,

respectively, a shiftable friction ring coöperating with said cone pulleys, and a bell-crank lever operated by said cam and adapted for shifting the friction ring. 10

In testimony whereof, I hereunto affix my signature.

OSCAR A. ALBRECHT.
